N. P. JULIEN

ELEVATOR

Filed Aug. 25, 1922

INVENTOR,
Napoleon P. Julien,

Harry W. Brown.
ATTORNEY.

UNITED STATES PATENT OFFICE.

NAPOLEON P. JULIEN, OF SPRINGFIELD, MASSACHUSETTS.

ELEVATOR.

Application filed August 25, 1922. Serial No. 584,198.

To all whom it may concern:

Be it known that I, NAPOLEON P. JULIEN, a subject to the King of Great Britain, residing at Springfield, county of Hampden, 5 Commonwealth of Massachusetts, have invented certain new and useful Improvements in Elevators, of which the following is a specification.

This invention relates to improvements in elevators of the type in which cables are used to support the car and counterweight. Such cables are usually carried around a hoisting drum, either with the single wrap or multiple wrap traction construction. In 10 the present invention it is designed to use drums with the single wrap traction construction. It has been found in practice that some of the strands of the wire cables on account of the wedging action and excessive wear between the grooves of the drum and the sides of the cables produces so much wear on comparatively few of the strands of the cable as to weaken them, and consequently the whole cable; necessitating the 15 substitution of new cables. This substitution of new cables is a very expensive part of the maintenance of this class of elevators.

An object therefore of the present invention is to provide means for overcoming this excessive wear on a few of the strands and thus prolonging the life of the whole cable. I accomplish this result by providing devices for successively and automatically rotating all of the cables about their axes for the purpose of presenting new wearing surfaces of the strands of the cable to the sides of the groove of the drum, whereby owing to the rotative movements 20 of the cables about their axes the entire circumferential surface of the whole cable will wear uniformly and thus prolong the life of the same.

The invention broadly considered comprises devices operable during the travel of the car and counterweight which will simultaneously impart a rotary or twisting movement to the cable strands and in opposite directions so that the twisting movement of one end of the cable will be counteracted by the twisting movement of the opposite end, thus maintaining the cable in good condition at all times.

Referring to the drawings:

Fig. 1 is a general elevational view showing the elevator well with the car in its up-

ward position and the counterweight in the corresponding lowest position, also showing the attachments for imparting rotary movements to the opposite ends of the 60 cables.

Fig. 2 is a sectional view taken in a plane represented by the line 2—2 of Fig. 1 looking towards the top of the car and showing the worm and worm gears connected to the 65 ends of the cable for imparting a rotary movement to the cables, and the ratchet device for operating the worm.

Fig. 3 is a sectional view taken in the plane represented by the line 3—3 of Fig. 2 70 showing two of the worm gears that are driven by the worm, and two of the cables being connected to the gears, also the bolts which are connected to the cables and gears and extend downward between the channel 75 irons of the framework of the car and the ball bearings at the lower ends of the bolts.

Fig. 4 is a side elevational view on a plane represented by the line 4—4 of Fig. 1 showing one end of the ratchet device for 80 operating the worm; the inclined or cam surface depending from the overhead framework at the top of the well of the building for operating the worm and ratchet.

Fig. 5 is a side elevational view on the 85 plane represented by the line 5—5 of Fig. 1 showing the ratchet mechanism of the upper end of the counterweight and at the lower end of the travel of the counterweight also the inclined or cam surface for operating 90 the ratchet.

Fig. 6 is a diagrammatic view showing a portion of a cable in the groove of the drum to illustrate the wearing effect.

Fig. 7 is a view illustrating the principle 95 of my invention.

Figs. 8 and 9 are details of the ratchet mechanism.

Referring to the drawings in detail:

The elevator car, indicated at 1, is shown 100 at the upper end of its run. The usual operating electric motor is indicated at 2, the traction drum at 3. Passing over the drum are the traction and lifting cables, five of which are shown, as indicated at 4, 5, 6, 7, 105 and 8.

Referring to Fig. 3 the wire cables 5 and 7 are secured to the blocks 9 in the usual manner by spreading strands of the cable and pouring in melted solder. It is to be 110 understood that the ends of all of the cables are secured to the blocks in the same way.

These blocks 9 are shown pinned to the bolts 10 and secured to the bolts 10 are the worm gears 11. These bolts extend downward between the webs of the channel irons 12 which 5 are secured to the top of the car. Their lower ends pass through the plate 13. 14 are ball race plates for receiving the balls of the bearing indicated at 15 and 16 is a plate 10 engaging the lower surfaces of the balls and 15 with which the securing nut 17 engages. Located on the top of the car and between the rows of worm gears 11 is the worm shaft 18. This shaft is mounted in bearings 19 and 20 on the plate 21. Secured to the opposite ends of the worm shaft 18 are the 20 ratchet wheels 22 which are engaged by the pawls 23 (see Figs. 8 and 9). These pawls are secured to the lever arms 24 which are loosely mounted on the worm 18, the pawl 25 being, as shown located between the arms 24' of the arm 24. The upper ends of these arms are provided with rollers 25 (see Figs. 2 and 4), which rollers engage the inclined surfaces 26 of the depending cam members 25 that are secured to the overhead framework of the elevator well a portion of which is indicated at 28.

For the purpose of actuating the arms 24 for holding the rollers 25 in contact with the 30 cam surfaces 26 weights 29 are provided which are secured to the arms 30 that are secured to the arms 24. 31 indicates a stop to limit the downward movement of the weight 29, and to accurately position the rollers 25 35 so that they will not pass by the lower ends 27' of the members 27.

It will be seen that when the car reaches the upward end of its travel the rollers 25 40 will engage the inclined plane or cam surfaces 26 causing the pawls 23 to engage the ratchet wheel 22 and impart rotary movement to the worm 18, which in turn, will rotate the gears 11, on one side of the worm 18 in one direction, and on the opposite side 45 of the worm 18 in an opposite direction, thus, imparting a rotary or twisting movement to the cables 4, 5, 6, 7, and 8.

For the purpose of simultaneously imparting a rotary or twisting movement to the 50 other end of the cables they are attached to the counterweight 32 in the same manner as that already described in connection with their attachment to the top of the car. A worm shaft 33 is suitably mounted for rotation in the bearings 32' on the upper ends of the bar 32' that support the counterweights. This shaft is provided at its opposite ends with ratchets 34 which are pinned to the shaft 33 as indicated at 35. 36 is a 55 pawl carried by the arm 37 which arm is provided with a roller 38, that engages the inclined plane or cam surface 39 of the member 40 that is secured to the framework at the bottom of the elevator well, whereby on 60 the descent of the counterweight the worm

shaft 33 will be rotated and in a direction opposite to the worm shaft 18 since the direction of the cam surface is reversed. The direction of movements of the lever arms 24 and 37 are indicated by the arrows 24' and 37'. The plan view of this shaft would be the same as that shown in Fig. 2. Secured to the lever 37 is a weight 41 by means of the arm 42, the purpose of which is to maintain the roller 38 in the same position or 75 alignment so that it will always engage the inclined surface 39.

Although I have shown ratchet mechanism at the opposite ends of the shaft 18 it is obvious that a single ratchet construction 80 at one end of the shafts 18 and 33 would be sufficient. By using the construction of worm gear and worm, there is a reduction movement between the shaft 18 and the cables for the purpose of imparting only a 85 small rotary movement to the cables at the ends of the travel of the car and counterweight when the car is at the upper ends of the travel the counterweight is at the lower end. 90

Referring to Figs. 6 and 7 which illustrates the position the cables assume in the grooves 43 of the drum 44, it will be seen that the strands of the cable at the opposite sides of the same are the ones that receive 95 the constant wear. This result is produced by the pinching or crowding effect due to the more or less V-shape of the groove 43, since the cable does not completely fill the groove. My invention is designed to overcome this wearing effect of the same strands which are constantly brought into contact with the groove. This is accomplished by providing devices to impart a rotary movement to one end of the cables as indicated 100 by the arrows 7' (see Figs. 6 and 7) to the cable 7 for example. The arrow 72 illustrates the idea of imparting rotary motion in an opposite direction to the opposite end of the cable 7, whereby the two rotary movements will counteract each other and thus maintain the original length of the cable. 105 By employing means to successively and automatically effect these rotary movements in a step by step manner the life of the cable 110 will be materially increased. 115

What I claim is:

1. In an apparatus for the purpose described, the combination, with the car, counterweight and traction drum and the car supporting cable, of means mounted on the car and counterweight for imparting a rotary or twisting movement to the ends of the cable. 120

2. In an apparatus for the purpose described, the combination, of devices secured to the opposite ends of the supporting cables, and means engaging the devices for imparting a rotary or twisting movement to the cables for causing the cables to progressively 125 130

change their contact surfaces which engage the grooves of the traction drum.

3. In a device for the purpose described, comprising in combination with the car, counterweight, traction drum, and cables of an elevator mechanism, of means for imparting a rotary or twisting action to the opposite ends of the cables during their travel, said means comprising a worm located on the car and counterweight respectively, means for operating the worm during the travel of the car and counterweight including cam surfaces, ratchet devices on each of the worms, operative means between the cam surfaces and the ratchets, whereby the worm may be operated and operative means between the worm and each of the cables.

4. A device for the purpose described, comprising in combination with the car, counterweight, traction drum, and cables of an elevator mechanism, of means for imparting a rotary or twisting action to the opposite ends of the cables, said means comprising a worm located on the car and counterweight respectively, means for operating the worm including cam surfaces, a device on each of the worms for rotating the same operative means between the cam surfaces and the devices, said means being at the end of the travel of the car and counterweight respectively, and operative means between the worm and each of the cables.

5. An apparatus for the purpose described and comprising in combination with the cables of an elevator mechanism, a gear secured to the ends of each of the cables, means carried by the car and counterweight respec-

tively for rotating the gears and the cables, means for causing the cables to be automatically rotated in opposite directions and including abutments, operative means between the abutments and the means on the car for rotating the gears, and means for returning and maintaining the gear operating means in their initial positions.

6. In a device for the purpose described, the combination with the car, counterweight, traction drum, and the supporting cables of an elevator mechanism, of means for successively and automatically imparting a slight rotary or twisting movement to the cables during the extreme run of the car and the counterweight, respectively, said means including gears secured to the ends of the cables, means for operating the gears in opposite directions comprising cam devices, an arm engaging the cam devices, said arm being operatively connected to the gear operating devices.

7. In an apparatus for the purpose described, the combination, of a worm shaft secured to the upper ends of an elevator car and counterweight respectively, worm gears secured to the ends of the cables and engaging the worm shaft, means for automatically operating the shaft during the run of the car and counterweight for imparting a turning or twisting movement to the ends of the cables and in opposite directions as described, whereby the wearing surfaces of the cables in their supporting drums will be changed.

NAPOLEON P. JULIEN.
